J. A. MILLEA.

STENCILING SET.

APPLICATION FILED AUG. 18, 1915.

Patented Mar. 14, 1916.

UNITED STATES PATENT OFFICE.

JOHN A. MILLEA, OF RENSSELAER, NEW YORK.

STENCILING SET.

1,175,542.

Specification of Letters Patent. Patented Mar. 14, 1916.

Application filed August 18, 1915. Serial No. 46,061.

To all whom it may concern:

Be it known that I, JOHN A. MILLEA, a citizen of the United States, residing at the city of Rensselaer, in the county of Rensselaer and State of New York, have invented 5 certain new and useful Improvements in Stenciling Sets, of which the following is a specification.

My invention relates to stenciling sets.

10 The object of my invention is to provide a stenciling set comprising a plate having a guide or handle secured thereto with convenient receptacle in the handle for retaining removable parts used in the operation of 15 stenciling, together with such other elements and combinations as are hereinafter more particularly set forth and claimed. I accomplish these objects by means of the mechanism illustrated in the accompanying drawings.

20 Figure 1. is a plan. Fig. 2. is a section along the line A—A on Fig. 1. Fig. 3. is a section along the line B—B on Fig. 1. Fig. 4. is a detailed sectional view with parts 25 broken away, of the handle bar F. Fig. 5. is the same view as Fig. 4 with the exception that the plate G therein is raised. Fig. 6. is a front elevation with parts broken away showing the manner of retaining the 30 stencil brush when not in use.

Similar letters refer to similar parts throughout the several groups.

The stencil plate C is constructed of any suitable, thin, preferably metallic material 35 and has portions cut away leaving the openings in the form of letters so that when the brush, containing paint, ink or other marking substance is drawn over the openings cut into the plate, there will be painted on 40 the box, barrel or other article on which said stencil plate is placed, the letters and figures which have been cut out of the plate. All this is done in the usual manner.

When the stencil is used for marking 45 boxes and barrels containing fruit, and especially apples, it is convenient and in some localities imperative, that the minimum size of the apples placed in the inclosure is of a certain number of inches, 2, 2 $\frac{1}{4}$, 2 $\frac{1}{2}$ 50 inches, etc. The name of the fruit or the name of the particular variety may be marked on the package.

I have, in the stencil plate, provided for marking the number of inches of the minimum size and when the minimum size is 2 55 inches, I do not paint over that portion of

the stencil which is cut for 2 $\frac{1}{4}$, 2 $\frac{1}{2}$ or any other size. For the purpose of inserting the name of the variety or kind of fruit, I cut away the plate at, preferably, the central portion thereof and bend the sides E of the opening upon itself and then form the overlapping strip F', making a slide-way between the portion E and the portion F' for the auxiliary plate H carrying the name to be displayed. I preferably construct a boss J projecting from the face of the plate C which will enter a receptacle or indentation K in the end of the plate H which will tend to hold the plate H in position. One edge 60 of the stencil plate C is attached to the handle bar F by means of suitable pins "f" and the handle bar is preferably provided with a beaded edge L and reciprocating longitudinally thereof I place the metallic 65 sleeve M which is adapted to close a portion of the slotted opening N. To the sleeve M is pivoted a bracket O and between the spring arms of which is placed a stencil brush P as shown in Fig. 6.

At one end of the slotted opening N in the handle bar is placed a right angled plate G, holding the same by means of a pin "g" passing through a slotted opening in that portion "h" of the right angled plate G 80 which engages the handle bar at the end of the opening N. I preferably bend the right angled portion "h" to form a hook "j" for convenience in lifting an auxiliary plate to the position shown in Fig. 5. Into the opening N and with one end thereof resting on the plate G, I place the removable auxiliary plates "H" from which I select one to place in position on the stencil plate which will enable me to paint on the package the particular name required.

The arrangement of this stencil device is such that the plate may be used very readily because the handle bar permits of its being lifted from a package and placed on another 100 without difficulty or fumbling. The arrangement of the removable auxiliary plates inclosed in the handle bar is very convenient and provides for marking packages containing different varieties of fruit much more 105 expeditiously than is the case with other stencil devices with which I am familiar.

My invention is simple in its construction and operation and performs its functions in an economical and satisfactory manner.

What I claim as my invention and desire to secure by Letters Patent is:

A stencil set adapted for marking packages comprising a stencil plate; a handle bar attached thereto; a series of movable auxiliary plates; means for retaining one of said auxiliary plates on the stencil plate when placed thereon and from which means it may be readily removed; said handle bar adapted to hold the auxiliary plates; all

substantially as described and for the purpose set forth.

In testimony whereof I affix my signature in presence of two witnesses.

JOHN A. MILLEA.

Witnesses:

FREDERICK W. CAMERON,
ELIZABETH H. WATERMAN.
